(57) **CLAIM**

The ornamental design for an enclosure, as shown and described.

DESCRIPTION

FIG. 1 is a front isometric view of an enclosure;

FIG. 2 is a top plan view of the enclosure of FIG. 1;

FIG. 3 is a bottom plan view of the enclosure of FIG. 1;

FIG. 4 is a left side elevational view of the enclosure of FIG. 1;

FIG. 5 is a right side elevational view of the enclosure of FIG. 1;

FIG. 6 is a front elevational view of the enclosure of FIG. 1; and,

FIG. 7 is a back elevational view of the enclosure of FIG. 1. The broken lines in the drawings illustrate portions of the enclosure which form no part of the claimed design.
